CLAIM

The ornamental design for a cartridge, as shown and described.

DESCRIPTION

FIG. 1 is a perspective view of a cartridge showing our new design;

FIG. 2 is a front view of the cartridge of FIG. 1;

FIG. 3 is a rear view of the cartridge of FIG. 1;

FIG. 4 is a right side view of the cartridge of FIG. 1;

FIG. 5 is a left side view of the cartridge of FIG. 1;

FIG. 6 is a top view of the cartridge of FIG. 1; and,

FIG. 7 is a bottom view of the cartridge of FIG. 1.

The broken lines are included for the purpose of illustrating portions of the cartridge that form no part of the claimed design.

1 Claim, 6 Drawing Sheets(56)
